UNITED STATES PATENT OFFICE.

THOMAS HEFFERNAN, OF LONDON, ENGLAND.

GOLF-CLUB.

1,088,571.

Specification of Letters Patent.

Patented Feb. 24, 1914.

Application filed July 25, 1913. Serial No. 781,115.

To all whom it may concern:

Be it known that I, THOMAS HEFFERNAN, a subject of the King of Great Britain and Ireland, residing at London, England, have 5 invented Improvements in Golf-Clubs, of which the following is a specification.

My invention relates to the clubs used in playing golf and it has more particular reference to clubs the striking faces of which 10 are of glass.

According to my invention I provide the face of the club with a glass face dovetailed into the wood or other material of the club head with the intervention of suitable cement or packing to allow of expansion. I have found that a club provided with a glass face as described is extremely effective and better results can be attained than with the ordinary clubs as now used. It 15 is to be noted that the glass face must not be held in place by engagement with pins, screws or the like as it is found that such arrangements result in splitting or breaking of the glass face.

20 Figures 1 and 2 show a driver head according to this invention in face view and cross section respectively.

25 *a* is the wooden head formed with a tapering recess the edges of which are dovetailed as indicated by the dotted line *b* to correspond with the edges of the glass plate *c*. The plate *c* is bedded on packing *d* such as chamois leather and the edges of the plate are coated with a packing of putty-like cement so as to permit the glass plate to expand without fracture; the packing has not the function of a spring cushion. When 30 the plate *c* has been inserted it is held in place by the attachment of the horn *e* of the club.

40 The head of the club is formed with one

or more holes pierced from the face of the club to the back which is not broadly new but I find that the resistance of the air upon the face of the club when "driving" a ball is 45 much reduced by forming holes *f* as illustrated and a correspondingly better result is attained by the player.

What I claim is:—

1. A golf club having a glass striking face 50 plate dovetailed into the material of the club head and interposed packing to allow of expansion of the glass, substantially as described.

2. A golf club, comprising a head formed 55 with a dovetail recess in its front face and having its end walls converging toward the upper end of the head, a glass striking face fitting within said recess and a horn carried by the lower face of the head and extending across the lower end of the dovetail recess and engaging the glass striking face and holding the same in the dovetail recess.

3. A golf club having a glass striking face secured therein and having a backing of 60 elastic material.

4. A golf club having a glass striking face secured therein and having a backing of 65 elastic material and a packing at the ends to allow of the expansion of the glass.

5. A golf club having a dove-tailed recess, a glass striking face within the dove-tailed recess an elastic backing between the rear face of the glass face and the club and a packing at the ends to allow of the expansion 70 of the glass.

Signed at London, England this 12th day of July 1913.

TOM HEFFERNAN.
